UNITED STATES PATENT OFFICE

117,264

DESIGN FOR A MAGNET TOY

Jack Galter, Chicago, Ill.

Application August 24, 1939, Serial No. 86,864

Term of patent 3½ years

To all whom it may concern:

Be it known that I, Jack Galter, a citizen of the United States of America, residing at 711 West Lake Street, Chicago, Illinois, have invented a new, original, and ornamental Design for a Magnet Toy, of which the following is a specification, reference being had to the accompanying drawing, forming a part thereof.

The figure is a perspective view of a magnet toy, showing my new design.

I claim:

The ornamental design for a magnet toy, substantially as shown.

JACK GALTER.
